UNITED STATES PATENT OFFICE

STANLEY W. NICHOLSON, OF TOLEDO, OHIO, ASSIGNOR, BY MESNE ASSIGNMENTS, TO
THE DURA COMPANY, OF TOLEDO, OHIO, A CORPORATION OF OHIO

WINDOW REGULATOR

Application filed March 23, 1926. Serial No. 96,819.

The invention relates to window regulators and is particularly applicable to window regulators for actuating wide, heavy windows such as used in buses. Some of the objects of the invention are to provide a simple construction of window regulator which may be cheaply manufactured; to provide a window regulator having a pivotal lifter arm arranged to exert a force upon the window substantially centrally thereof in all positions of angular adjustment of the arm; and to provide a simple arrangement of counterbalance for the weight of the window.

With these as well as other objects in view, the invention resides in the novel features of construction and combinations and arrangements of parts as more fully hereinafter set forth.

In the drawings:

Figure 1 is an interior side elevation of a portion of a bus employing window regulators embodying my invention;

Figure 2 is an enlarged interior side elevation of a portion therewith with the internal panel removed;

Figure 3 is a cross section on the line 3—3 of Figure 2;

Figure 4 is a view similar to Figure 2 and showing a modified window regulator;

Figure 5 is a cross section on the line 5—5 of Figure 4.

In the present instance, I have shown a bus having windows which are raised and lowered by window regulators embodying my invention. This bus has the adjacent window openings 1 with the jambs 2 therebetween provided with guideways 3 for the windows 4. These windows are vertically movable from positions closing the openings into the chambers 5 which are located below the sills 6 at the bottoms of the openings and between the jambs 2 and the inner and outer panels 7 and 8, respectively.

For raising and lowering the windows which are relatively wide and heavy, I have provided a window regulator for each window. Since the arrangement of each window regulator is the same, but one window regulator will be described in detail. This window regulator has the pivotal lifter arm

9 which is slidably connected to the window as by means of the bearing 10 secured to the outer end of the arm and slidably engaging in the channel 11 which embraces and is secured to the lower edge of the window. The window regulator also has the rack 12 which is pivotally connected to the arm 9 and which meshes with the pinion 13, this latter being driven from the crank 14 through suitable irreversible drive mechanism 15 which permits driving the pinion from the crank but prevents driving the crank from the pinion.

It is very important that the force exerted by the lifter arm in raising the window be applied substantially centrally of the window in all positions of angular adjustment of the arm and for this reason the arm is made relatively long and its pivotal end portion is located in the chamber 5 for receiving the adjacent window. The arm is connected by the pivot 16 to the free apex of the triangular mounting plate 17 which is secured to a jamb and is located laterally inward from the path of travel of the window movable into the chamber in which the mounting plate extends so that the mounting plate and lifter arm will not interfere with the travel of this window. The mounting plate is preferably provided with the transverse inwardly extending flanges 18 at its edges for reinforcing the mounting plate.

The rack 12 is longitudinally slidable within the channel 19 formed in the inner side of the jamb and the pinion crank and associated irreversible drive mechanism are preferably formed as a unitary structure and secured to the jamb above the sill 6 so that the crank will not interfere with the arrangement of the seats of the bus.

For counterbalancing the weight of each window, I have provided the coil spring 20 which is also located in the channel 19 of the jamb and is hooked at its lower end to the upper end of the rack and at its upper end to the upper end portion of the jamb.

From the above description, it will be readily seen that the construction of my window regulator is very simple and furthermore is such that it may be formed largely of stampings. It will also be seen that by reason of

the lifter arm of each window regulator overlapping the adjacent window opening, a substantially centrally located vertical lift may be provided for each window inasmuch as 5 comparatively long lifter arms may then be used. Furthermore, it will be seen that the window regulator lends itself readily for installation in a bus or other vehicle and permits locating the crank so that it will not 10 interfere with the arrangement of the seats.

The modified construction of window regulator shown in Figures 4 and 5 comprises the pivotal lifter arm 21 which has its outer end operatively connected to the lower edge of the window 22 and its inner end pivotally connected to the rack 23, the lifter arm being pivotally mounted intermediate its ends upon the triangular mounting plate 24 and preferably at an apex thereof. The rack 23 extends upwardly within the channel 25 formed in the inner side of the jamb and is reciprocated in the same manner as the rack 12 from the crank 26 secured to the jamb above the window sill 27. For counterbalancing the 20 weight of the window, I have provided the convolute or spiral springs 28 upon opposite sides of the mounting plate, each having its outer end hooked and engaging the transverse pin 29 upon the arm and its inner end engaging in slots in the ends of the pin 30 forming the pivot for the arm and rigidly secured to the mounting plate. By reason of the two counterbalancing springs, smaller springs 25 may be used than if one counterbalancing spring were employed and furthermore, the effect exerted by these springs is balanced on the opposite sides of the arm.

What I claim as my invention is:

1. In a vehicle having adjacent window 10 openings and chambers for the openings and also windows for the openings movable into the chambers, a window regulator for actuating one of the windows including a pivotal lifter arm having a portion extending within a chamber and operatively connected to the window and a second portion extending within an adjacent chamber, a pivotal mounting for said second portion within said last-mentioned chamber, and means for operating said lifter arm.

2. In a vehicle having adjacent window 15 openings and chambers below the openings and also windows for the openings movable into the chambers, a window regulator for actuating one of the windows including a pivotal lifter arm having its free end portion extending within a chamber and operatively connected to the window and its pivotal end portion extending within an adjacent chamber, a mounting plate within said adjacent chamber and pivotally connected to the pivotal end portion of said arm, said mounting plate and arm being out of the path of travel 20 of the window movable into said adjacent

chamber, and means for operating said lifter arm.

3. In a vehicle having adjacent window openings and chambers below the openings, windows for the openings movable into the chambers and jambs between the openings and chambers, a window regulator for actuating one of the windows having a pivotal lifter arm extending into adjacent chambers and operatively connected at one end to the window, a mounting plate upon the jamb between said chambers pivotally connected to the other end of said arm, a member pivotally connected to said arm and extending upwardly adjacent said jamb, and means for longitudinally adjusting said member. 75

4. In a vehicle having adjacent window openings and chambers below the openings, windows for the openings movable into the chambers and jambs between adjacent openings and chambers provided with longitudinally extending channels, a window regulator for actuating one of the windows including a lifter arm extending within one of said chambers and operatively connected to the window 80 and also extending within an adjacent chamber and pivotally mounted therewithin, a longitudinally reciprocable member connected to said lifter arm and extending within the channel in said jamb between said adjacent openings and chambers, and means for actuating said reciprocable member. 85

5. In a vehicle having adjacent window openings and chambers below the openings, windows for the openings movable into the chambers and jambs between adjacent openings and chambers provided with longitudinally extending channels, a window regulator for actuating one of the windows including a lifter arm extending within one of said chambers and operatively connected to the window 90 and also extending within an adjacent chamber and pivotally mounted therewithin, a longitudinally reciprocable member connected to said lifter arm and extending within the channel in said jamb between said adjacent openings and chambers, and means for actuating said reciprocable member. 95

6. In a vehicle having a window opening, a window for the opening, a jamb at one side of the opening provided with a longitudinally extending channel and a sill at the lower end of the opening, a regulator for actuating said window including a pivotal lifter arm operatively connected at one end to said window, a mounting for pivotally supporting said arm at one side of said jamb, a rack pivotally connected to said arm and extending within the channel in said jamb and a crank mounted upon said jamb above said sill and operatively connected to said rack. 110

7. In a vehicle having adjacent window openings and chambers below the openings 120

and also windows for the openings movable into the chambers, a window regulator for actuating one of the windows including a lifter element having a portion extending 5 into a chamber and operatively connected to the window and another portion extending into an adjacent chamber, means within said last mentioned chamber and engageable with the second portion of said lifter element for 10 movably mounting the same, and actuating means for said lifter element.

8. In a vehicle having adjacent window openings and chambers below the openings, windows for the openings movable into the 15 chambers and jambs between the openings and chambers, a window regulator for actuating one of the windows having a pivotal lifter arm extending into adjacent chambers and operatively connected at one end to the window, a mounting plate upon the jamb between said chambers pivotally connected to the other end of said arm, and actuating 20 means engageable with said pivotal lifter arm.

25 In testimony whereof I affix my signature.
STANLEY W. NICHOLSON.
